UNITED STATES PATENT OFFICE.

RODNEY J. WOOD, OF DAYTON, OHIO.

CREDIT-FILE.

1,313,150.

Specification of Letters Patent. Patented Aug. 12, 1919.

Application filed July 20, 1915. Serial No. 40,827.

To all whom it may concern:

Be it known that I, RODNEY J. Wood, citizen of the United States, residing at Dayton, in the county of Montgomery and State 5 of Ohio, have invented certain new and useful Improvements in Credit-Files, of which the following is a specification.

My invention relates to filing systems and apparatus and more particularly to what is 10 known to the trade as a credit file especially adapted for the use of retail merchants in keeping systematic records of business transactions.

The object of the invention is to simplify 15 the structure as well as the means and mode of operation of such devices whereby they will not only be cheapened in construction but will be more efficient in use, positive in operation, capable of being easily and rapidly operated, and unlikely to get out of repair.

A primary object of the invention is to provide full and complete protection against 20 the dishonesty of employees or the accidental loss of records of sales or other data by rendering the information of data contained 25 on sales records or other filed matter quickly available for the information of the clerk or others yet inaccessible for removal or destruction.

A further object is to provide a filing apparatus which will be compact in form, light 30 in weight, pleasing in appearance, and flexible or elastic in character to permit the filing 35 of sales records or other data under a few or a great many different titles or headings and to further permit the filing of a single record slip or data sheet or a great many of such slips or sheets in each account or under 40 each heading.

With the above primary and other incidental objects in view, as will more fully appear in the specification, the invention 45 consists of the features of construction, the parts and combinations thereof, and the mode of operation, or their equivalents, as hereinafter described and set forth in the claims.

Referring to the drawings, Figure 1 is a 50 perspective view of the assembled apparatus. Fig. 2 is an interior side view of the same viewed from the right in Fig. 1. Fig 3 is a perspective view of a single file unit comprising a temporary file section and a permanent file section connected one to the other to move in unison as hereinafter de-

scribed. In this figure the permanent file section has been partly broken away to show in section the nested arrangement of the leaves or holders and the frame therefor. 60 Fig. 4 is a detail plan view of a portion of a temporary file section. Fig. 5 is a detail sectional view of one of the leaves or holders showing the method of supporting the identification card. Fig. 6 is a detail view 65 of the locking detent and means for releasing same. Figs. 7 to 16, inclusive, illustrate modifications of the device.

Like parts are indicated by similar characters of reference throughout the several views.

The apparatus forming the subject matter hereof comprises two file bodies which for convenience will be referred to as the temporary file and the permanent file. The 75 temporary file is at all times accessible to the clerks and receives the sales slips for the day at the time of the transaction. The permanent file is never accessible to the clerks. To this file the sales slips are transferred from the temporary file by the proprietor or other authorized person at the end of business each day. The corresponding members of the two file bodies are so connected one with the other that they will 80 move in unison. The construction is such that when the temporary file is open to a certain account or heading the permanent file is automatically opened to the same account or heading. The permanent file is 85 inclosed in a suitable locked housing which will permit the contents of the permanent file to be observed but which prevents direct access thereto except by an authorized person. 95

By this construction the clerk may ascertain instantly the total amount due upon any customer's account by looking in the permanent file within the inclosing housing but a dishonest clerk is prevented from removing any part of the customer's previous sales slips either as a favor to the customer or after having collected payment for the full amount due to avoid the necessity for accounting for all of the receipts and thus 105 enable him to retain a portion for himself. The fact that the credit sales for past business are maintained in a locked inclosure accessible only to the proprietor or duly authorized person insures that the merchant will receive the value of each account. 110 The apparatus thus protects every credit

sales record against accidental loss or intentional abstraction and obviates the necessity of transferring the record of credit sales to a ledger or other permanent account book. The proprietor is by this means enabled to instantly ascertain the condition of his business by observing the permanent file for the totals of amounts due from various credit customers and by observing the temporary file for the business done during the day. To ascertain the present day business it is not necessary with this apparatus to examine each and every credit account but the temporary file automatically indicates those credit customers waited upon and in whose accounts additional credit transactions have been made during the day. The merchant is therefore saved the time and labor of examining accounts in which no transaction has been recorded and his examination is confined entirely to accounts active during the day. It not only enables the merchant to ascertain quickly and easily the total amount of credit business transacted but it also saves time and labor in taking off the balance of these credit sales at the end of the day. Thus, if only twenty five of a total of one hundred credit customers have had credit transactions during the day the merchant takes his balance from only twenty five accounts and is not compelled to examine the remaining seventy-five inactive accounts. The file is in normally locked condition and when so locked the contents of the file are masked or covered thereby preventing a customer or other unauthorized person from surreptitiously examining the credit accounts of other customers or removing from the file credit slips of their own account, thereby reducing the actual amount payable to the merchant. In order to further discourage unauthorized opening of the file an alarm is provided which indicates to any one within hearing the fact that the file has been released, and separate registers are provided for each clerk to indicate the number of times the file has been opened, and an additional counter indicates the number of times the permanent file has been opened. The file is designed to afford ease and rapidity of operation and to this end it affords a constantly visible index of the customer's accounts rendering it unnecessary to refer to a separate index. Being of comparatively small size and light in weight it is easily moved from one place to another. The sales slips being inclosed within a metallic casting or housing are not only protected against loss or abstraction but are also protected against loss by fire.

Referring to the drawings, 1 is the housing or case divided by a transverse partition 2 into two compartments 3 and 4. The housing 1 is preferably, though not neces-

sarily, constructed of metal and is provided with a locked closure 5 for the compartment 3. The compartment 3 is adapted to contain the permanent file, the contents of which may be observed through a glass panel 6 in the closure 5. In order to provide additional illumination within the compartment the side panels 6 of the housing may likewise be formed of glass, if so desired. The closure 5 is provided with a slot or contracted opening 7 at its forward edge registering with a pocket 8 formed upon the inner side of the partition 2 through which may be deposited "C. O. D." slips or record slips or data sheets other than credit slips.

The compartment 4 at the forward end of the housing is adapted to contain the temporary file and is open at its front and top to permit easy access thereto. The units or sections and cover or mask are normally latched or temporarily locked to prevent tampering with the contents. These are easily and quickly released by keys or buttons hereinafter described.

The closure 5 is preferably hinged and is normally locked by any suitable form of locking means such as is indicated at 9. An operation counter 10 is provided by which is indicated the number of times the closure 5 is opened.

The temporary and permanent files comprise an equal number of swinging sections or frames each having thereon a plurality of retaining devices or holders for the sales slips. The corresponding sections or units of each file are connected one to the other to operate in unison. The swinging sections or units 11 of the temporary file unit are preferably mounted in stepped or spaced relation each succeeding frame or section being pivoted in a plane higher than the preceding section whereby the sections or frames are made to overlap, as clearly shown in Figs. 1 and 2. Each of these frames or sections comprise a flat plate 12 hinged or pivoted upon transverse trunnions 13. Attached to the face of each unit 12 are a plurality of overlapping leaves or holders 14, one for each account carried by the unit. These leaves or holders are attached to the plate 12 at one edge only and are capable of being flexed outward against the tension of the material. Beneath the overlapping leaves or holders 14 there is provided a projecting shelf or ledge 15. The construction is such that the sales slips or data sheets may be thrust behind any one of the series of leaves or holders where it will be held by the tension of the leaf with its lower edge resting upon the shelf or ledge 15.

Inasmuch as it is intended that the sales slips or data sheets shall be transferred from the temporary file to the permanent file at the end of each business period, it is not

necessary that these holders shall be of great capacity. A capacity of a few sales slips or sheets will be found sufficient for ordinary conditions of use.

- 5 In using the device a leaf or holder is allotted to each credit customer and the customer's name is preferably attached at the upper edge of the exposed portion of the leaf. This may be done by pasting or gluing slips of paper or cards to the face of the leaf or the leaf may be provided with a panel in which a card or piece of paper containing a name may be engaged. In Fig. 5 there is shown in detail a simple construction for retaining the name card or identification tag in place. In this construction the leaf is perforated to form a rectangular panel, the material removed being bent rearward and thence upon itself in a direction parallel with the plane of the leaf to form two oppositely disposed U-shaped bights 16 in which the edges of the card or identification tag may be engaged.
- A mask or cover 17 comprising a flat plate is pivotally mounted at the front of the housing and is adapted to cover the initial unit or section of the temporary file series. The cover 17 and the temporary file units 11 may be oscillated about their pivotal connections, as indicated in Fig. 2. Each unit in the file is independent of every other unit of the same file. The construction is such, however, that the oscillation of any unit of the series necessarily causes the oscillation of all the units in advance of that selected, while those to the rear thereof remain at rest. Inasmuch as each unit extends slightly above the preceding unit the name cards or identification tags carried by the consecutive units will be exposed, as shown in Fig. 1, thereby forming a convenient index by which any particular account may be quickly located.

The permanent file units located within the compartment 3 comprise a plurality of units or sections 19 to which are attached a plurality of overlapping leaves 20 between which the sales slips transferred from the temporary file are engaged in the manner before described. Inasmuch as the permanent file contained in the compartment 3 receives the sales slips representing more or less extended business periods, the capacity of the holders or retaining devices for sales slips must be greater than those of the temporary file. Each permanent file unit comprises a main frame or housing 21 having a dependent flange 22 at its top edge forming a stop for the leaves 20. At one end it is provided with a fixed plate 23 against which the terminal leaf 20 of the series bears. To afford greater capacity the leaves or holders 20 are offset, as indicated at 24. The wing portion of the leaf at the inner side 65 of the offset 24 is attached to the back of the

main frame or housing 21. The offset 24 forms a stop for the inserted sales slips, which rest at their lower edges on a shelf or ledge 25 projecting from the main frame or housing 21. The offset leaves 20 are nested within the frame or housing, as shown in Fig. 3, whereby the free wings of said leaves normally lie in a plane substantially common with the face of the frame or housing 21. They are, however, capable of being flexed outward to accommodate an excessive number of sales slips, as indicated at the right in Fig. 3. Like the leaves of the holders of the temporary file units, those of the permanent file 80 units are also provided with name cards or identification tags. The accounts of the temporary and permanent files are arranged in corresponding relation. That is, each particular credit customer's account is found 85 in the identically same position in both the temporary and permanent files. The first unit or section of the permanent file contains the same accounts or headings as the first unit or section of the temporary file and 90 these accounts or headings are arranged in the same order. Likewise the accounts and order of arrangement thereof upon the second unit or section of the temporary file are identical with those upon the second section 95 of the permanent file. The corresponding sections or units of the temporary and permanent files are connected one to the other by intermediate connecting links 26 pivotally connected at opposite ends with their 100 respective sections or units. The arrangement is such that the first unit or section of the temporary file is so connected with the first unit of the permanent file, the second unit of the temporary file with the second 105 unit of the permanent file, etc. There is provided for the permanent file a cover plate or mask 27 pivotally connected at 28 and connected with the mask or cover plate 17 of the temporary file by a connecting link 110 29. These links 26 and 29 extend through suitable openings in the partition 2 and serve to oscillate the units or sections of the permanent file in unison with the oscillation of the corresponding units or sections of the temporary file. It is to be understood that the temporary file contained in compartment 4 of the housing is at all times accessible to the clerk while the compartment 3 is maintained locked thereby rendering the permanent file inaccessible except by the operation of the temporary file as described.

To insure that both the temporary and permanent files are closed after each operation, springs 30 are attached to the opposite 125 sides of the mask or cover 27 of the permanent file. The mask is operated in the opening movement against the tension of the springs 30 which tend to return the mask or cover 27 and with it all operated sections 130

or units to normal position upon their release. The mask or cover 27, being connected as before described with the cover or mask 17 of the temporary file, said covers 5 or masks operate in unison. The units or sections of the temporary file, being likewise under control of the cover or mask 17 during the closing movement and further connected with the corresponding units or 10 sections of the permanent file, the units of both files are returned to normal position in unison.

To prevent tampering with the contents of the file by unauthorized persons and to 15 prevent the surreptitious examination of accounts by customers or others, there is provided a latch or lock adapted to hold the file members in closed position. This latch or lock comprises a pivoted arm 31 attached 20 to the lower front portion of the partition 2, the upper end of which extends through a suitable keeper 32 and is adapted to engage a lug or shoulder 33 upon the link 29 connecting the covers or masks 17 and 27. The 25 construction is such that so long as the upper end of the detent arm 31 is in engagement with the shoulder 33 the covers 17 and 27 cannot be drawn forward. Therefore the several file units are held in normal or closed 30 position.

To disengage the detent and release the file unit, there is provided upon the exterior of the main housing a depressible button or key 34 having a stem 35 engaging a lip or flange 36 upon the detent arm 31. In the 35 drawings there have been shown three of these buttons or depressible keys lettered respectively A, B, and C, any one of which is adapted to cause the disengagement of the 40 detent arm from the shoulder 33 to release the file units. In the present construction a separate depressible button or key is provided for each clerk, viz: one for clerk A, another for clerk B, and a third for clerk C.

45 In order to record the number of times each clerk has manipulated the file there is provided adjacent to each of these buttons a counter 37, the actuating shaft of which is provided with a bifurcated arm 38 engaging a stud or pin 39 upon the stem 35 of the corresponding button or key. The construction is such that at each depression of the key or button the corresponding counter will be caused to add one to the total shown 50 upon such counter or register. In order that a particular clerk key or button may not be employed during his absence each key or button is provided with an independent lock 39' by which any or all of the keys 55 may be locked against operation.

60 It is obvious that in lieu of the separate keys each of which is adapted to independently operate the detent, the said keys or buttons may be associated with combination lock mechanism whereby the keys must

be operated in a predetermined order or in certain combinations in order to release the file units. Such particular lock mechanism, while desirable, is not essential to the successful operation of the file and forms no 70 part of the present invention other than as hereinafter set forth in the claims.

The operation of the device is as follows: Assuming that clerk A is about to make a credit sale to the customer Jacobs, the clerk 75 will press his release button marked A at the left of the cabinet which will oscillate the detent arm 31 out of engagement with the stop or shoulder 33 upon the link 29 connecting the masks 17 and 27 and at the same 80 time will oscillate the operating lever 38 of the corresponding counter to add one upon the register corresponding to the key or button operated. Having thus unlocked the temporary file, he will open the said file 85 at the proper point as indicated by the position of the name of the customer in the index formed by the projection of the identification tags of each unit beyond the margin of the preceding unit. In the present 90 instance he will draw forward the mask 17 and first two units of the series to expose the account holder or leaf previously assigned to the customer Jacobs. The forward movement of the mask 17 and initial 95 file units of the temporary file cause a like movement of the mask 27 and corresponding file units of the permanent file contained within the compartment 3 beneath the locked transparent cover. The corresponding 100 holder or leaf assigned to customer Jacobs in the permanent file is thus exposed and the clerk by looking through the transparent cover of the compartment 3 ascertains from the footing of the uppermost 105 sales slip in the permanent file that the total of customer Jacobs's credit purchases to date is eight dollars and ninety-eight cents. The clerk then carries this total eight dollars and ninety-eight cents forward onto 110 the current sales slip preparatory to entering thereon the customer's present purchases.

The present purchases entered upon the sales slip are added to the previous footing and the sales slip is then inserted in the 115 proper holder or leaf of the temporary file. Likewise when customer James makes additional purchases the clerk, opening the file in the manner before described, ascertains by looking through the transparent cover 120 of the compartment 3 that the total of customer James's purchases to date is three dollars and four cents. He enters this sum, three dollars and four cents, at the top of the sales slip and adds thereto the items of 125 his purchase, which as shown in Fig. 1 amount to thirty seven cents, making a total of three dollars and forty-one cents which footing he enters upon the sales slip and places this slip in the proper holder or leaf 130

of the temporary file. If a customer appears during the absence of the proprietor and wishes to pay his account, the clerk by opening the file to the proper place may ascertain from the footing shown through the transparent top of the permanent file the total of such customer's indebtedness. For instance, he might ascertain that customer Joy is indebted to the amount of ten dollars 10 and forty-five cents. If customer Joy paid five dollars on this account the clerk would make out a credit slip for the five dollars, showing the balance due of five dollars and forty-five cents which credit slip he would 15 place in the temporary file in the usual manner. He cannot, however, gain access to the permanent file to remove therefrom any of Joy's sales slips. He must account for the five dollars collected for if he should fail to 20 do so and fail to place the credit slip in the temporary file the customer Joy, learning that he is still charged with the full amount, would present his receipt and insist upon proper credit being given. If the clerk 25 should place the credit slip in the temporary file but fail to account for the money the proprietor would necessarily discover the discrepancy in taking off the balance for the business of the day. The cash received on 30 credit accounts must always equal the credit slips found in the temporary file. The use of the locked permanent file prevents the clerk from abstracting sales slips from the account of customer Joy to the amount 35 of five dollars which would leave the customer's account in proper balance, thus enabling the clerk to retain the amount received on account for his own use. At the end of the business for the day the 40 proprietor or other authorized person, by examining the sales slips in the credit file, may ascertain the total of the business for that day. Referring to Fig. 1, it will be seen that this can be readily done as the file 45 instantly shows that transactions were made in the credit accounts of customers Horn, Hays, Jacobs, James, Koors and Kist and also as clearly shows that no transactions occurred in the accounts of customers Hand, 50 Joy, Cain and Kemp. Therefore the proprietor will disregard the last mentioned accounts and will confine his attention entirely to those accounts in which sales slips have been entered in the temporary file. 55 Having ascertained the total of the credit business transacted during the day and that the cash on hand from payments on credit accounts balances with credit slips which may be placed in the temporary file during 60 the day, the proprietor will then unlock the cover of the permanent file and transfer each credit slip from the temporary file to the corresponding holder or leaf of the permanent file, thus leaving the temporary file 65 empty at the beginning of each business period. The proprietor may at any time ascertain the total of outstanding accounts by observing the footings of the various accounts through the transparent cover of the permanent file and adding thereto the 70 amount of transactions of the present business period represented by the sales slips in the temporary file. Under ordinary circumstances the temporary file holders or leaves will contain but a single sales slip or at 75 most a very few sales slips concerning several transactions during a single business period. Such sales slips, when few in number, are less likely to become lost or misplaced than when large numbers of sales 80 slips are open for removal or examination by any person who may desire to do so. In the present construction all sales slips except those for current transactions are maintained in the locked compartment which 85 provides absolute protection against the dishonesty of employees and against accidental loss or displacement of the slips. While these sales slips may be removed only by the proprietor or other authorized person, 90 the total of the previous sales is instantly ascertainable by any clerk who may be authorized to receive money on account or for the purpose of carrying such footing forward to current sales slips. By preventing the removal of the sales slips representing previous purchases from the file the incentive for dishonesty is removed as the clerk must necessarily account to the proprietor for any credits shown by credit slips 95 100 in the temporary file and must account to the customer for failure to make such credit entry as will reduce the total of the past account which he is prevented from reducing by removal of sales slips. 105

While the construction shown in Fig. 1 has been found to be a convenient, economical and efficient arrangement, it is obvious that the several parts may be differently arranged in relation one with the other. For 110 example, the temporary and permanent files may be arranged either one above the other or side by side with the temporary file on either side of the permanent file. Likewise, in lieu of pivoting the file units for oscillatory or swinging movement, the file units may be connected one to the other for sliding or reciprocatory movement, or the holders or containers for the sales slips may be carried upon revoluble rollers or drums. 115 In view of the disclosure herein made many modifications and variations of the construction and arrangement of parts may be made, a few of which have been illustrated in the drawings and are hereinafter described. 120 125

In Fig. 7 there is shown a modification in which the units or carriers 40 comprising the temporary file and the corresponding units 41 comprising the permanent file are supported upon shafts 42 common to 130

the corresponding units of both series. The units 41 comprising the permanent file are contained within the locked transparent closure or housing 43 and are oscillated by the 5 oscillation of the temporary file units 40, the movement of which is transmitted to the corresponding permanent file units through the common shaft 42.

In Fig. 8 there is shown a modification in 10 which the temporary units or carriers 44 are supported upon oscillatory arms 45 connected to and moving in unison with the permanent file units or carriers 46 contained within the transparent inclosure or housing 47. The construction is such that the permanent units or carriers 46 within the housing are oscillated to and from normal position by the oscillation of the corresponding temporary carriers or units 44, 15 the movement of which is transmitted through the oscillatory arms 45.

In Fig. 9 there is shown a structure differing somewhat in appearance but embodying the same elementary features before described. In this construction the carriers or 25 units are arranged in horizontal position and separated into two stacks 48 and 49. The stack 48 comprises the temporary units or carriers 50 which are arranged to slide 30 horizontally into and from normal position within the stack in a manner similar to the movement of a desk or table drawer. The permanent file units or carriers 51 contained in the stack 49 are connected with the corresponding units 50 of the temporary series by intermediate links or rods 52. The stacks 48 and 49 of units or carriers are separated one from the other and a transparent locked housing or inclosure 53 is interposed there- 35 between. The construction and arrangement is such that the withdrawal of any unit or carrier 50 from the stack 48 will cause the withdrawal of the corresponding units or carriers 51 from the stack 49 into a position 40 to be observed within the housing or inclosure 53.

In Fig. 10 there is shown a construction having the general appearance of that disclosed in Fig. 1 and heretofore described. 50 However, in lieu of the oscillatory units or carriers of the primary construction, the temporary units 54 and permanent units or carriers 55 of the present construction are adapted to slide to and fro and the corresponding units of the respective files are connected one to the other by intermediate links or rods 56. The construction is such that upon drawing forward any unit or carrier 54 of the temporary file the corresponding unit or carrier of the permanent file will likewise be drawn forward. The units or carriers are thus given a reciprocatory movement to and from normal position in lieu of the oscillatory movement before described.

In Fig. 11 there is shown a further modification in which the leaves or holders for the sales slips or data sheets are carried upon rollers or drums 57 and 58 mounted upon a common shaft. The drum 57 comprises the temporary file while the drum 58 70 which is inclosed within a transparent locked housing or inclosure 59 constitutes the permanent file. By the rotation of the drum 57 to bring the desired account to position to be seen the drum 58 within the housing is 75 likewise rotated. These drums 57 and 58 may be extended to any desired length and thereby made to carry any desired number of accounts or separate classifications. Likewise the drums may be made with any number of sides thereby providing additional series of holders.

In Fig. 1 there is shown a modification of the construction shown in Fig. 11 in which the drums 57 and 58 are arranged in parallel relation and are rotated in unison by means of a belt or chain 60 engaging sprocket wheels or pulleys 61 upon the shafts of the respective drums. In this construction, as in Fig. 11, the drum 58 80 constituting the permanent file is inclosed within a transparent locked housing 59.

In Fig. 13 is shown a construction which may be substituted for the drums 57 and 58 in either of the constructions shown in Figs. 95 11 and 12. In this modification the main shaft 62 is provided with disks or collars 63 rotating therewith in which are pivoted at 64 the units or carriers 65. The carriers or units 65 are each provided with a spring 66 100 which tends to oscillate the carrier or unit 65 about its pivotal connection 64 from the position shown in solid lines to that shown in dotted lines at the left in said figure. The shaft 62 is rotated by manual effort to bring 105 the desired unit or carrier into position to be seen. The rotation of the shaft presents the carriers or units successively against a stop or detent 67 by which the units or carriers are arrested while the shaft 62 and disk 63 110 continue to rotate, thereby turning the unit or carrier 65 about its pivotal connection 64 and placing the spring 66 under tension. As the shaft 62 and disk 63 continue to rotate the forward unit 65 will be withdrawn 115 from beneath the stop or detent 67 whereupon the spring 66 will operate to turn the unit or carrier downward to the position indicated by dotted lines, thereby exposing 120 the next succeeding unit or carrier. Each 120 unit or carrier is limited in its oscillatory movement under the influence of the spring 66 by its engagement with the shaft or trunnion of the next succeeding unit or carrier as shown about the lower portion of said 125 figure.

In Fig. 14 there is shown a construction somewhat similar to that shown in Fig. 1 in

which, however, the carriers or units 68 oscillate upon vertical axes. The units or carriers 68 comprising the permanent file are inclosed within a transparent locked 5 housing 69 and are connected by links 70 with corresponding units or carriers 71 constituting the temporary file.

While the overlapping spring leaf holders heretofore described in connection with Fig. 1 are preferable, it is obvious that other 10 forms of holders such as resilient wire loops 73, Figs. 14 and 15, may be employed in lieu thereof. Likewise in lieu of the overlapping arrangement of the sales slips or data 15 sheets the said sheets or slips may be spaced one from the other upon the carriers or holders, as shown in these figures.

In Fig. 15 there is shown a transparent locked housing or inclosure 74 having there- 20 in a plurality of oscillatory carriers or units 75 each provided with a handle 76 projecting through an arcuate slot in the housing by which said units or carriers may be os- 25 cillated from a vertical or upright to hori- zontal or reclining position. In lieu of the temporary file of like construction, there is shown in this figure a simple and well known 30 form of stick file 77 upon which the sales slips or data sheets may be temporarily placed and from which they may be trans- 35 ferred to the permanent file comprising the oscillatory units or carriers 75.

While in each of the constructions heretofore referred to a single housing or inclosure 35 is provided for the plurality of units or carriers constituting the permanent file, it is obvious that each of these file units or carriers may be provided with a separate cover or inclosure such as the cover leaf 78 of 40 transparent material shown in Fig. 16.

It is obvious that this filing device, par- 45 ticularly when constructed similar to the forms shown in Figs. 1, 7, 9 and 10 may be mounted as a drawer in a desk or cabinet to slide to and fro or it may be an independent structure as shown in the drawings. It is desirable but not essential that a cash 50 drawer to receive the amounts paid on account be provided in conjunction with the file devices herein disclosed.

While this invention has been described particularly in connection with a credit sales transaction, it is to be understood that it is not limited to such use but may be applied 55 to other purposes than the protection of credit accounts such as library records, stock invoices and similar purposes. It is furthermore to be understood that it is not limited to the filing of credit sales slips but for some 60 classes of business it may be desirable to employ instead of a sales slip a card on which is entered the customer's ledger account which is carried in the permanent file upon which amounts may be entered from

slips placed in the permanent file. By such 65 use of ledger cards the transfer would be made in writing in lieu of the physical trans- 70 fer of the slips from the temporary to the permanent file. This system would enable the clerk to examine the entire ledger ac- 75 count of the customer without being able to remove said card or make erasures or changes thereon.

Referring to Fig. 2, there is shown upon the mask 27 an arm 79 adapted to trip a 75 spring actuated hammer 80 causing it to en- gage the bell 81 to sound an alarm whenever the file is opened. The arm 79 also closes an electrical contact 82 to complete a circuit from the battery 83 or other source of elec- 80 trical energy through the lines 84 to a lamp 85 which may be located in any convenient position to illuminate the permanent file units.

From the above description it will be ap- 85 parent that there is thus provided a device of the character described possessing the particular features of advantage before enumerated as desirable but which obviously is susceptible of modification in its form, proportion, detail construction, or arrange- 90 ment of parts without departing from the principle involved or sacrificing any of its advantages.

While in order to comply with the statute the invention has been described in language 95 more or less specific as to certain structural features, it is to be understood that the means and construction herein described comprise but one mode of putting the invention into effect and the invention is therefore claimed broadly within any of its possible forms or 100 modifications within the scope of the ap- pended claims.

Having thus described my invention, I 105 claim:

1. In a filing device as described, a plural- 110 ity of movable file units separated into two series, connections between the correspond- ing units of the separate series whereby said units will move in unison and a protective inclosure for one of said series of file units, 115 the other series of file units being free for access.

2. In an appliance of the character de- 120 scribed, the combination of two groups of movable units or carriers of like number, the said groups being adapted to removably support corresponding sets of data sheet, and connecting means between correspond- 125 ing units or carriers of the two groups whereby the movement of any one of the units or carriers of one group produces movement of the corresponding unit or carrier of the opposite group so that the corresponding data sheets of the two sets are simultaneously exposed, and a protective housing inclosing the units or carriers of one group which permits the observation of

the data sheets carried thereby but prevents the removal, transposition or insertion of data sheets into the units or carriers of such group while the other group of units or carriers is open and exposed for ready access.

3. In a filing device, a plurality of movable file units separated into two series, a housing inclosing one series of units, and means for simultaneously operating corresponding units of both series.

4. In a filing device, a housing separated into two compartments, a transparent closure for one of the compartments, a series of movable file units in each of the compartments and interconnections between the corresponding units of the separate series whereby the operation of a file unit of one series will cause a simultaneous movement of the corresponding unit of the other series.

5. In a filing device as described, a plurality of movable filing units arranged in pairs, interconnections between the members of each pair whereby they will move in unison, and means for normally rendering one member of each pair of units inaccessible, the other member of each pair of units being always accessible, for the purpose described.

6. In a filing device, two series of file units comprising a temporary and a permanent file adapted to contain separated portions of the same accounts or data classifications the corresponding units of the respective series being fixed in relation one with the other, and a normally locked housing inclosing the permanent file preventing access thereto while permitting the observation of the contents of said file.

7. In a filing device, a series of temporary file members, and a series of permanent file members, corresponding units of the respective series being arranged in constant relation one with the other, and means for normally preventing the removal of the contents of the permanent file members while permitting observation thereof.

8. In a filing device, two series of movable file units the members of which are mounted for like movement and interconnections between the corresponding file units whereby the operation of a file unit of one series will cause the simultaneous movement of the corresponding unit of the other series through a similar path of travel.

9. In a filing device, two series of file units comprising a temporary and a permanent file adapted to carry separated portions of the same accounts or data classifications arranged therein in corresponding order, interconnecting means between the corresponding units of the temporary and permanent files, whereby the exposure of the contents of a unit of one file will effect the simultaneous exposure of the contents of the corre-

sponding unit of the other file, and means for normally preventing the removal of or additions to the contents of the units of the permanent file.

10. In a filing device, a normally accessible temporary movable file, and a normally inaccessible permanent movable file to which the contents of the temporary file are transferred, and means for operating said files in unison.

11. In a filing device, a normally accessible temporary movable file, and a normally inaccessible permanent movable file to which the contents of the temporary file are transferred, and interconnecting means to operate the permanent file by the operation of the temporary file.

12. In a filing device, a normally accessible temporary file, and a permanent file adapted to contain separated portions of the same account or data classification, a normally locked housing having an observation space therein inclosing the permanent file, and interconnecting means whereby the contents of the respective files may be exhibited in unison.

13. In a filing device as described, duplicate file units movable in parallel relation one to the other and interconnecting means for operating one file unit by the operation of its duplicate.

14. In a filing device, duplicate file bodies one of which is normally accessible and the other of which is normally inaccessible for removal and insertion of data sheets, each adapted to carry separated portions of the same accounts or data classifications, and means for operating the file bodies in unison to simultaneously display both portions of the same accounts or classifications carried by the separate file bodies.

15. In a filing cabinet, a main frame, a plurality of swinging units mounted therein for oscillatory movement about horizontal axes, and a plurality of overlapping flexible leaves arranged in a horizontal series carried by each unit and attached thereto adjacent to the underlying edges of the leaves between which data sheets may be inserted with their vertical marginal portions exposed.

16. In a filing device as described, a plurality of file units separated into two series, connections between the corresponding units of the separate series, whereby the movement of one of said units controls the movement of the corresponding unit of the other series, and a protective inclosure for one of said series of file units, the other series of file units being free for access.

17. In a filing cabinet, a plurality of units mounted therein for oscillatory movement about horizontal axes, a plurality of overlapping leaves arranged in horizontal se-

ries carried by each unit between which data sheets may be inserted with their vertical marginal portions exposed.

18. In a file as described, a plurality of 5 movable units, a plurality of data sheet holders arranged in horizontal series carried by each unit, a plurality of identification tags carried by each unit, one identification tag being associated with each holder, each unit being normally extended beyond the margin of the preceding unit to display the identification tags carried thereby when the said units are in closed relation.

19. In a file as described, a plurality of 15 independently movable units, a plurality of vertically disposed overlapping leaves carried by each unit between which data sheets may be inserted, an identification tag for each data sheet holder, the units being normally arranged in overlapping relation whereby the identification tags of each unit will be normally displayed.

20. In a filing device as described, a plurality of oscillatory units separated into 25 two series, and operative connections between corresponding units of the separate series whereby said corresponding units will be oscillated in unison to simultaneously display corresponding accounts or data classifications.

21. In a filing device, two series of oscillatory file units, and links pivotally connected with the corresponding units of the respective series to cause said corresponding 35 units to move in unison.

22. In a filing device, a series of movable file units, a movable mask normally covering the initial unit of the series, and a retracting spring actuating the mask to return 40 the operated units to normal.

23. In a filing device two separate file members in which are normally concealed separated portions of the same account or data classification, and means for automatically exhibiting the contents of one file member upon the exhibition of the contents of the other file member whereby the separated portions of the same account or data classification will be simultaneously displayed.

24. In a filing device as described, two file units, a movable mask for each unit, and interconnections between the masks whereby said masks will be moved in unison.

25. In a filing device as described, two file 55 units, a movable mask for each unit, and means for simultaneously withdrawing both masks to expose the units concealed thereby.

26. In a filing device as described, two file units, a movable mask for each unit, and 60 an intermediate connection whereby one mask will be operated by the operation of the other.

27. In a filing device, two series of oscillatory file units, each series of units carry-

ing a plurality of accounts or data classifications arranged in corresponding order, one series constituting a temporary file and the other a permanent file, intermediate connections between corresponding units of the separate series whereby said units will be 70 operated in unison, and means for normally preventing the abstraction of data sheets from the units of the permanent file but adapted to permit the observation of said data sheets within the said file, substantially as specified.

28. In a filing device, a locked housing, a plurality of normally inaccessible movable file units within the housing, a plurality of overlapping leaves arranged in 80 horizontal series carried by each unit between which data sheets may be inserted with the vertical marginal portions thereof exposed, an observation space in said housing through which the exposed vertical marginal 85 portions of the data sheets may be observed, and means extending to the exterior of the housing for presenting the file units to view.

29. In a filing device, a series of normally concealed file compartments, a movable mask 90 for the said file compartments, means for rendering the contents of the file compartments inaccessible, and means for moving the mask to expose the contents of the file to view while maintaining them inaccessible. 95

30. In a filing device a normally accessible file member, a normally inaccessible file member and intermediate operating means for exhibiting the contents of the inaccessible file upon the exhibition of the contents of the accessible file. 100

31. In a filing device, a series of file compartments, and a transparent cover therefor through which the contents of the compartments may be observed but adapted to 105 prevent the removal of said contents, a second series of file compartments correlated with the first mentioned series, and means for simultaneously displaying the contents of complementary compartments. 110

32. In a filing device two series of correlated file members, means for rendering the contents of the file members of one series inaccessible for removal or addition, and means for simultaneously displaying the contents of complementary file members of the respective series. 115

33. In a filing device as described, a plurality of movable carriers, a locked housing inclosing the carriers and having an observation space therein through which the contents of the carriers may be observed, and an independent operating member for each carrier extending to the exterior of the housing and moving through paths of travel 120 similar to the paths of travel of the correlated carriers for moving the carriers substantially as specified. 125

34. In a filing device a main frame, a support mounted therein for oscillatory movement about a horizontal axis, a plurality of overlapping leaves carried by said support, said leaves being arranged in a horizontal series with each succeeding leaf extending laterally beyond the preceding leaf of the series thereby forming a succession of pockets or receivers for data sheets 10, open on their lateral or vertical sides, whereby the vertical marginal portions of the data sheets inserted therein will be exposed to view.
35. In a filing device a main frame, a support therein mounted for oscillatory movement about a horizontal axis, a plurality of overlapping leaves arranged in horizontal series carried by said support, and identification means carried by the individual leaves 15 of said series.
36. In a filing device, a plurality of oscillatory arms, a plurality of file units connected to and moving in unison with the oscillatory arms, said units being separated 20 into two series, and a locked housing having an observation space through which the contents of the units may be observed inclosing one series of units, the construction being such that the oscillation of an arm will simultaneously oscillate corresponding units 25 of both series.
37. In a filing device, a plurality of filing units arranged in substantially upright position and separated into two series and each 30 capable of a lateral movement, intermediate connections between the corresponding units of the respective series whereby said corresponding units will move in unison and means for preventing the removal of the contents of the units of one series.
38. In a file device a housing, a plurality of swinging file units pivoted therein upon horizontal axes to swing forwardly and rearwardly, said swinging units being normally positioned in echelon, whereby the top 35 or free edge of each unit will be exposed beyond the edge of the preceding unit, a plurality of containers for data sheets arranged in a horizontal series upon each of said swinging units, the data sheet containers of each succeeding unit being concealed by the preceding unit of the series and identification means pertaining to each container carried upon the exposed portions of the 40 swinging units whereby the containers and contents thereof are normally concealed from view while the identification means pertaining to such containers is normally displayed when said plurality of file units are in their closed relation.
39. In a filing device as described, a plurality of movable filing units arranged in pairs, inter-connections between the members of each pair, whereby the movement of one 45 unit of a pair will control the movement of the other unit of the same pair, and means for normally rendering one member of each pair of units inaccessible, the other member of each pair of units being always accessible for the purpose described.
40. In a filing device, two series of movable file units, members of which are mounted for like movements, and inter-connections between corresponding file units of the respective series whereby the operation of each 50 file unit of one series will control the movement of the corresponding unit of the other series.
41. In a filing device, two series of file units comprising a temporary and a permanent file adapted to carry separated portions of the same accounts or data classifications arranged therein, in a corresponding order, interconnecting means between the corresponding units of the temporary and permanent files, whereby the exposure of the contents of a unit of one file will control the exposure of the contents of the corresponding unit of the other file, and means for normally preventing the removal of, or additions to the contents of the unit of the permanent file.
42. In a filing device, a normally accessible, temporary movable file, and a normally inaccessible, permanent, movable file to 55 which the contents of the temporary file are transferred, and interconnecting means to control the operation of the permanent file by the operation of the temporary file.
43. In a filing device as described, duplicate file units movable in parallel relation one to the other and interconnecting means for controlling the operation of one file unit by the operation of its duplicate.
44. In a filing device, duplicate file bodies 60 one of which is normally accessible and the other of which is normally inaccessible for removal and insertion of data sheets, each adapted to carry separated portions of the same accounts or data classifications, and means for operating the file bodies to display both portions of the same accounts or classifications carried by the separate file bodies.
45. In a filing device as described, a plurality of oscillatory units separated into two series, and operative connections between corresponding units of the separate series whereby said corresponding units will be oscillated to display corresponding accounts 65 or data classification.
46. In a filing device as described, two file units, a movable mask for each unit, and means for controlling the movement of one of said masks by the operation of the other mask.
47. In a filing device, a series of file compartments, and a transparent cover there-

for through which the contents of the compartment may be observed, but adapted to prevent the removal of said contents, a second series of file compartments correlated 5 with the first mentioned series, and means for displaying the contents of the complementary compartments.

48. In a filing device, a plurality of oscillatory arms, a plurality of file units connected to and moving in unison with the oscillatory arms, said units being separated 10 into two series, and a locked housing having an observation space through which the contents of the units may be observed dis- 15 closing one series of units, the construction being such that the oscillation of an arm

will oscillate corresponding units of both series.

49. In a filing device, two series of file units comprising a temporary and permanent file, and a normally locked housing inclosing the permanent file and preventing access thereto, and means permitting the observation of the contents of said file controlled by the operation of the tempo- 20 25 rary file.

In testimony whereof I have hereunto set my hand this 17th day of July, A. D. 1915.

RODNEY J. WOOD.
